W. J. LANDRY.
CARD HOLDER FOR GARMENT HANGERS.
APPLICATION FILED JUNE 25, 1919.

1,321,926.

Patented Nov. 18, 1919.

UNITED STATES PATENT OFFICE.

WALLACE J. LANDRY, OF BATON ROUGE, LOUISIANA.

CARD-HOLDER FOR GARMENT-HANGERS.

1,321,926.

Specification of Letters Patent.

Patented Nov. 18, 1919.

Application filed June 25, 1918. Serial No. 308,712.

To all whom it may concern:

Be it known that I, WALLACE J. LANDRY, a citizen of the United States, residing at Baton Rouge, in the county of East Baton Rouge and State of Louisiana, have invented certain new and useful Improvements in Card-Holders for Garment-Hangers, of which the following is a specification, reference being had to the accompanying drawings.

This invention relates to the art of card holders, and particularly an improved price, size, style and lot number card holder, especially adapted for use in connection with garment hangers.

It is well known that in department stores and the like that garments for sale are supported on hangers which are suspended from racks or from hooks in floor cases, and usually the price and lot number card, including size and style, is connected to the sleeve of the garment. In order to ascertain the price and the lot number with this method, it is very inconvenient and troublesome, due to the fact that the card very often becomes entangled between the sleeve and the body of the garment or between the sleeve or portions of the other garments since they are suspended very close together, especially when having reduced sales. Other methods of attaching the price card embodies the idea of attaching or otherwise fastening the card on the side of the hanger. This method is also inconvenient and very troublesome, requiring the salesman to pull back the side of the coat or other garment in order to see the side of the hanger on which the price card is fastened. This takes time, and also it may happen that the shoulder of the garment will fall from engagement with the hanger, requiring the salespeople to replace the garment. To go through a number of garments in this way requires time, considerable patience and while the salespeople are consuming time in this manner, the purchaser may lose patience or become dissatisfied and then decide on not buying.

This invention relates to an improved price, lot number, size and style card holder especially adapted for a particular kind of hanger, especially one that has an enlargement at the upper central portion to which a hook is connected for suspending the hanger in the floor case or on a rack. This enlargement not only extends upwardly from

the diagonal sides of the hanger but also it is constructed considerably thick so that a very wide holder may be applied to the upper oppositely inclined edges of the enlargement, whereby a very wide card may be held in the holder.

It will be observed that a card holder of this character will facilitate the sales of garments considerably due to the fact that there is but little time utilized in ascertaining the size, lot number, price and style of the garment. A saleslady can at a glance see practically all the price and style cards of each row of garments, due to the fact that the enlargement protrudes a good distance above the collar of the garment. Also, the saleslady can see the prices and the styles and the lot numbers from either side of the floor case, there being no necessity of separating the garments or finding the card on the sleeves or pulling back the side of the coat or other garment to see the price card fixed to the side of the hanger.

The present invention aims to avoid the various disadvantages herein named in regard to the old method of applying the price and style card to the hanger.

The invention further aims to provide a very simple, efficient and practical holder which may be manufactured at a relatively low cost and sold at a reasonable price.

The invention further aims to provide a holder consisting of an elongated frame bent substantially midway its ends to provide oppositely inclined parts with elongated openings therein, said parts being so arched as to permit the price and size, style and lot number card holders to be inserted under the inclined parts and the upper inclined edges of the enlargement of the hanger.

The inventor in this application is well aware that there have been numerous card holders devised, therefore, it is the aim not to claim a card holder broadly, but it is the aim of the present invention to claim a very specific construction of card holder, as distinguished from the card holders which embody the disadvantages as previously disclosed.

While the design and construction at present illustrated and set forth is deemed preferable, it is obvious that as a result of a reduction of the invention to a more practical form for commercial purposes, the invention may be susceptible to changes, and the right to these changes is claimed, provided they

are comprehended within the scope of what is claimed.

The invention comprises further features and combination of parts as hereinafter set forth, shown in the drawings and claimed.

In the drawings:

Figure 1 is a perspective view of several hangers, showing garments suspended thereon, illustrating the enlargements of the 10 hangers projecting above the collars of the garments, thereby disclosing the price and style cards arranged in the holders.

Fig. 2 is an enlarged detail perspective view of a garment hanger showing the card holder as applied.

Fig. 3 is a plan view of the central portion of a hanger showing the card holder.

Fig. 4 is a sectional view on the line 4—4 of Fig. 3, and

Fig. 5 is an enlarged detail view of the holder detached.

Referring to the drawings, 1 designates the hanger as a whole and which comprises a body 2 and the outwardly and downwardly 25 inclined arms 3 which are arranged at an obtuse angle. The body 2 extends considerably above the arms 3 and is also considerably thicker than the arms, the reason for which will be pointed out later. Connecting the outer end portions of the arms and arranged transversely of the hanger is a beam 4 for the purpose of strengthening the hanger. Pivoted at 5 is a clamping bar 6 which, when disposed in clamping position relatively to the bar 4, is in parallelism with the bar 4. This clamping bar 6 is designed for the purpose of clamping a waist band of a skirt or the lower ends of a pair of trousers, so that the skirt and 40 coat of a coat suit and the trousers and the coat and vest may be hung upon the same hanger. When the bar 6 is in clamping position, its free end is secured by the clamping loop 7 which is pivotally connected to 45 the bar 4. This loop 7 is disposed in close position to the extremity of the bar 6 so that it can be easily moved to a position free from the extremity of the bar 6. The loop 7 will remain in engagement with the bar 6, due to the friction between the loop 50 7 and the bar, particularly when a garment is clamped between the bars 4 and 6.

The enlargement 2 is provided with a pair of inclined edges 8 which are disposed at 55 an obtuse angle, and owing to the body 2 being of considerable thickness, a very wide card holder may be secured to said edges 8, in order to receive a very wide price card. In fact, by means of the holder a 60 pair of cards may be held on the hanger. The holder 9 comprises a frame constructed from a single piece of sheet metal bent to provide portions arranged at an obtuse angle in order to engage the edges 8. These angularly extending portions 10 of the holder

frame are provided with elongated openings 11 through which the data or selling information relative to the garment may be easily observed on the card 12. The angularly extending parts of the holder are bent 70 as shown at 13. Adjacent to where the angularly extending parts are bent to engage the edges 8 and adjacent the opposite or remote ends of the parts, are bent at 13^a so as to arch the bodies of the angularly 75 extending parts of the holder, whereby price, size, style and lot number cards may be inserted between the angularly extending portions of the holder and the edges 8 of the enlargement 2 of the hanger. When the 80 cards are so arranged, the selling information thereon is plainly visible, without necessitating the saleslady pulling back the side of the coat or looking for the card in the folds of the garments or between the 85 sleeves or otherwise hidden. The saleslady may very easily at a glance observe all the price cards in each row and from either side of the floor case or from either side of the rack and in this manner facilitate the 90 sale of the garments.

The holder is secured upon the inclined edges of the enlargement 2 by means of small screws, sprigs or other suitable fastening means 14. A central portion of the 95 holder, adjacent the apex or where the angularly extending parts of the holder are bent from each other is provided with an opening 15 through which the hook 16 of the hanger extends. In fact, when applying 100 the holder, the hook may be inserted through the opening and the holder moved to a position to engage the inclined edges, after which the securing means 14 may be arranged in position. The holder may be detached by removing the fastening means 105 and raising the holder so as to disengage the hook 16.

Adjacent the diagonal opposite longitudinal edges of the angularly extending parts 110 of the holder they are bent as shown at 13^b, so as to close the diagonal opposite portions of the arches of the angularly bent parts of the holder, whereby price cards may be inserted from diagonal opposite sides of the 115 angularly bent parts of the holder. In other words, the price card may be inserted in the holder from one side of the hanger, while another price card may be inserted in the holder from the diagonal opposite 120 side of the hanger.

The invention having been set forth, what is claimed as new and useful is:

1. The combination with an ordinary garment hanger provided with a central projection extending upwardly from the garment shoulder supports of the hanger and having a label receiving edge positioned in a plane a substantial distance above the collar of the garment, and a holder attached to 130

said edge and adapted to hold a label in place on said edge, whereby the label may be read viewing the projection on a plane inclined from the edge without separating 5 the collar from the projection.

2. The combination with an ordinary garment hanger including a substantial projection rising upwardly from a common union of the garment shoulder supports of 10 the hanger, said projection having inclined label receiving edges extending downwardly and outwardly in opposite directions, where-

by said labels may be read from either end of the hanger upon inclined planes from the labels, of a single sheet metal holder corresponding to and attached to said edges for holding the labels on both edges. 15

In testimony whereof I hereunto affix my signature in the presence of two witnesses.

WALLACE J. LANDRY.
